UNITED STATES PATENT OFFICE.

ELMER E. KRUMBEIN, OF WOMELSDORF, PENNSYLVANIA.

DIRIGIBLE LAMP.

1,186,914.

Specification of Letters Patent. Patented June 13, 1916.

Application filed March 4, 1915. Serial No. 12,048.

To all whom it may concern:

Be it known that I, ELMER E. KRUMBEIN, a citizen of the United States, residing at Womelsdorf, in the county of Berks and State of Pennsylvania, have invented a new and useful Dirigible Lamp, of which the following is a specification.

This invention relates to dirigible lamps especially designed for use in connection with motor vehicles, although it is to be understood that the same can also be used on other forms of vehicles.

One of the objects of the invention is to provide a lamp of this type having a stationary casing, the lamp and its support being revoluble within the casing, thus to cast the light rays in a desired direction.

A further object is to provide a lamp which, in view of the fact that the casing thereof does not stir, can be made of any attractive shape.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

In the accompanying drawings the preferred form of the invention has been shown.

In said drawings:—Figure 1 is a side elevation of a lamp embodying the present improvements, a portion of a mud guard and of a steering knuckle of a motor vehicle being shown. Fig. 2 is an enlarged vertical longitudinal section through the lamp. Fig. 3 is a section on line A—B Fig. 2.

Referring to the figures by characters of reference G designates a portion of a front mud guard of a motor vehicle and K designates a portion of a steering knuckle.

The housing of the lamp constituting the present invention has been indicated at 1 and can be of any shape and proportions desired. This housing is fixedly mounted on the mud guard G and is provided with ventilating openings 2 in its top, while the front of the housing is rounded and has an opening 3 extending through approximately 180 degrees.

55 A cylinder 4 is mounted for rotation in the housing, there being bearing faces 5 within

the housing for engagement with the outer surface of the cylinder and said housing being also engaged and retained by shoulders 6 provided along the top and bottom of the opening 3 in the housing. A lamp support of any suitable construction is mounted upon the bottom of the cylinder 4 and rotates therewith, this support being indicated at 7. The said support may carry one or more incandescent lamps, indicated at 8 and these lamps project into a hood 9 the front of which is disposed back of an opening 10 in the wall of cylinder 4 and has a lens 11. The hood 9 is provided at its back end with a reflector 12. A ventilating opening 13 may be provided in the top of the hood and another ventilating opening 14 may be provided in the top of cylinder 4.

A downwardly extending stem 15 is connected to the center of the bottom of cylinder 4 and is adapted to be rotated when the front wheels of the vehicle are turned about their knuckles K. In order to properly connect the stem 15 to the running gear, a lazy 75 tongs 16 is preferably provided, the upper end of the lazy tongs being attached to the stem 15 while the lower end is attached to the knuckle K in any preferred manner whereby when the knuckle is turned, the lazy 80 tongs 16 and the stem 15 will also be turned.

The parts are so positioned that when the front wheels are arranged to travel straight ahead, the hood 9 is located to throw the light rays directly forward through the 90 opening 3 in the housing 1. When the front wheels are turned to the right or to the left, a corresponding movement will be imparted to the cylinder 4 and the hood 9 so that light rays will be correspondingly turned to the 95 right or to the left. As the front of the housing is formed with the elongated opening 3 extending through approximately 180 degrees, it will be apparent that this turning of the lamp will not result in the light rays 100 being obstructed by the housing 1.

What is claimed is:—

The combination with a lamp supporting structure, of a housing fixed upon said structure and having a front opening extending 105 from one side to the other, a cylinder mounted for rotation within the housing and having an opening in the wall thereof at its front and a heat outlet opening in its upper end, a hood secured within said cylinder and 110 having a flared open end extending about the opening in the front of the cylinder, a
